CURTAIN ROD THREADING DEVICE

Charles D. Brobst, Aurora, Ill., assignor to Russell W. Allen and Loran Tower, both of Reading, Mass.

Application April 19, 1938, Serial No. 202,958

1 Claim. (Cl. 223—105)

The present invention relates to curtain rod threading devices such as are used to facilitate threading a curtain rod through the hem of a curtain or like hanging and the invention aims to improve generally existing devices for this purpose.

A preferred embodiment of the invention is illustrated in the accompanying drawing wherein

Fig. 1 is a face view of my improved threading device ready to be inserted in one end of a curtain rod;

Fig. 2 is a similar view illustrating the threading device in engagement with the curtain rod, a portion of the latter being shown in section; and

Fig. 3 is a sectional view through the curtain rod on the line 3—3 of Fig. 2, the threading device being shown in edge elevation.

According to the invention, my improved threading device comprises a threading tip or head 10 of suitable material and a spring wire closed retaining loop 11 having its free ends embedded within or otherwise suitably secured to the head 10. The retaining loop 11 is adapted to be inserted in one end of a flat curtain rod 12 to frictionally engage the walls thereof so as to maintain the head 10 securely at the forward or entering end of the rod 12.

The threading tip or head 10 may be formed of any suitable material, as for example wood, metal 30 or a molded plastic composition, and preferably is of a width and thickness slightly in excess of the width and thickness of the curtain rod so as to maintain all portions of the curtain hem open and spaced from the entering edges of the curtain rod. The forward end of the tip or head 10 may be tapered inwardly, vertically and horizontally as at 13 to present a smooth blade-like entering edge 14, and the rear end may be similarly tapered as at 15 to enter the channelled end of a 40 flat curtain rod as shown in Fig. 3.

The retaining loop 11 is advantageously formed of a single piece of spring wire, the ends of which are embedded in or otherwise secured as at 16 to the head 10, providing a closed pointed end 17 and elongated yieldable sides 18. The loop is so constructed that in its normal condition (see Fig.

1) the spacing between the sides 18 is greater than the width of the curtain rod, the sides tapering toward the more pointed closed end 17. Thus, when the loop is inserted in the curtain rod, the sides 18 are compressed and frictionally engage the inner walls of the channelled rod 12 throughout substantial lengths, the tension of the spring arms 18, being substantially at right angles to the inner wall of the curtain rod, aiding in preventing separation of the head 10 from the adjacent end of the curtain rod 12.

It will be apparent that the rear end of the tip or head 10 need not be tapered as at 15 but may be formed with a flat end engaging the end of the curtain rod 12, as the particular spring 15 loop 11 engages the walls of the rod 12 in such a manner as to hold the head against the end of the rod.

In use the wire loop portion of the threading device may be readily inserted within the channel of a curtain rod, the side arms 18 automatically bearing against the inner wall of the rod to hold the device securely in place. The assembled rod and device may then be inserted through the hem of the curtain, the enlarged head 10 smoothly guiding all portions of the hem outwardly so that it will not be snagged by any rough edge at the entering end of the curtain rod.

Having described the invention, what I claim as new is:

A curtain rod threading device comprising an elongated elliptical wire loop having a closed end pointed to readily enter the channel of a curtain rod, the side arms of said loop being normally spaced apart a distance greater than the width of 35 said channel and being compressible inwardly upon insertion in the channel to frictionally engage the inner walls of the curtain rod throughout a substantial length, and a threading tip secured to the free ends of the loop and retained 40 thereby against the end of the rod, the side arms of said loop engaging the channel under tension directed substantially at right angles to the wall of the channel and throughout elongated areas substantially inward and spaced from said tip. 45

CHARLES D. BROBST.
